UNITED STATES PATENT OFFICE.

CARLOS CAMPANILE, OF ENSENADA, ARGENTINA.

PADLOCK.

1,389,858.

Specification of Letters Patent. Patented Sept. 6, 1921.

Application filed April 28, 1921. Serial No. 465,109.

To all whom it may concern:

Be it known that I, CARLOS CAMPANILE, a subject of the King of Italy, residing at Ensenada, Province of Buenos Aires, Argentina, have invented certain new and useful Improvements in Padlocks, of which the following is a specification.

This invention relates to an improved padlock with a device for detecting and indicating when the same has been opened, and has for one of its objects the provision of a padlock equipped with a locking device so combined that when operated to unlock or open the same, a card placed within the padlock will be torn, the card being so arranged that it may only be removed after the padlock has been opened.

Another object of this invention is the provision of a padlock of the above kind, provided with sight-opening, which may be in the form of a window, and a cover, whereby the card may be inspected without the necessity of opening the padlock.

The padlock according to this invention may be of any suitable type as regards the locking mechanism, and either one end of the key itself or a separate piece operated by the same may be employed to operate the bolt.

An essential feature of the invention consists in a particular piece operated by the key and arranged to slide within a guide, said piece being provided with one or more projections adapted to enter into holes formed for that purpose in a card placed within the padlock. Besides, the usual bolt which at one end engages in a recess formed at the end of the shackle of the padlock, is operated by the aforesaid piece.

In the preferred embodiment the card is secured in position by means of a hinged cover, locked at one of its sides by the shackle of the padlock when in its closed position, so that in order to remove the card, the lock will first have to be opened, while by such opening or unlocking operation the card will be torn.

In order that the invention may be clearly understood and carried into practice without difficulty, a preferred embodiment of the same has been shown in the accompanying illustrative drawings, wherein:

Figure 1 is a perspective view of the pad-

lock with its cover or lid raised and without a card. 55

Fig. 2 is an elevation of a card.

Fig. 3 is a front elevation of the closed padlock, with the cover and card removed.

Fig. 4 illustrates a longitudinal section of the same, in its locked position. 60

Fig. 5 is a side view, with the cover and window in open position.

Fig. 6 is a sectional view, illustrating the mechanism of the lock as seen from the rear.

Fig. 7 shows a cross sectional view, the card having been torn. 65

Fig. 8 is a perspective view similar to Fig. 1 of a modified construction in which the key is inserted at the front part of the lock, instead of through the bottom. 70

Fig. 9 is a longitudinal section, similar to Fig. 4, of said modification.

In all the figures, similar reference numbers have been used to indicate like or corresponding parts. 75

The padlock in accordance with this invention substantially consists of a casing 1, in the interior of which is mounted the locking bolt 2, slidably mounted in a guide 3. The bolt 2 tends to constantly remain in its locked position under the action of the spring 4 and has its locking end engaged in a notch or recess 5, formed at the end of the shackle 6 of the padlock. The shackle 6 is mounted to move on a pin 7 secured in the casing 1; and to insure freedom of movement and proper accommodation of the free end of the shackle to the body of the lock, the opening in the shackle for the pin 7 is in the form of an elongated slot 8. 90

The key 9 for the lock may be arranged to directly operate the locking mechanism, as in the case of the form shown in Figs. 1 to 7, inclusive, wherein the key passes through the ward device 10, being provided with a projection 11 for that purpose. 95

In the modified construction shown in Figs. 8 and 9, in which the key 9^a is inserted through the front side, said key acts on a sleeve 10^a in the ward device which in turn by means of a suitable projection 12 operates the locking mechanism. 100

When turning the key to open the lock, the tooth or projection 11 or 12, according to the case, will cause the horizontal displacement of an operating member 13 along

a closure plate 20 formed with a guide slot 14 in which slide two projections 15, secured to said operating member. A spring 16 tends to hold said operating member in its 5 position of rest. After performing a certain part of its travel, an arm 13^a on the member 13 strikes against an arm 2^a of the bolt and pushes the same along, against the action of the spring 4, whereby the bolt is 10 disengaged from the recess 5 in the shackle. This operation permits the opening of the padlock which will be facilitated by the action exerted by the spring 17 which is secured to the guide 3 and bears against the 15 shackle end.

The card 18 is provided with two holes 19 of suitable shape so as to exactly fit the two projections 15 of the member in its position of rest, and is placed in the padlock 20 in flat condition on the plate 20 which closes the compartment containing the locking mechanism. After the card is positioned, a frame 21 is brought to bear upon the card, this frame 21 being hinged at 22 to the base 25 of the casing 1 and provided at its opposite side with a laterally bent flange or extended portion 23, having an opening 24 through which enters the free end of shackle 6 and also having a cut away part 25 for the reception of a nose formed on the pivoted end of said shackle.

With the parts of the padlock in their locked position, the shackle 6 will prevent the frame 21 from being opened, so that it 35 will be impossible to remove the card without first unlocking the padlock.

The frame 21 may be provided with a suitable sight-opening preferably closed by a glass 26, in order to be able to see whether 40 the card has or has not been torn, without the necessity of opening the padlock. For the protection of said glass, a suitable cover 27 is secured by means of a hinge at 27', at one side of the frame 21 and a spring 28 is 45 provided to normally keep the cover in its closed position. The cover 27 is formed with a projection 29 to facilitate the opening thereof. If desired, the cover may also be provided with a suitable fastening pin, 50 adapted to be inserted into the casing and engage in a recess formed in the part 13 in such a way that by a slight movement of the key it may be released.

From the foregoing description, the operation of the padlock according to this invention will be readily understood. The card being provided with a signature or other means of definite identification and its removal from the padlock only being 55 possible after the latter has been opened by its proper key, it will at once be seen that one can at any time determine whether the padlock has been opened and if such opening has been effected by the persons possessing the key.

It will be evident that several modifications of construction and detail may be introduced without departing from the scope of this invention, as clearly defined in the claims hereto annexed.

70

Having now described my said invention, I declare that what I claim as new and desire to secure by Letters Patent, is:—

1. A padlock with means for detecting the unlocking of the same, comprising a 75 locking mechanism provided with means for tearing a card or the like placed within the padlock; and a plate for covering said card, hinged at one side of the padlock and having a portion at its free end bent at right 80 angles to the plate, said bent portion being provided with a hole and a projection for co-operating with corresponding parts of the lock shackle, the parts being so arranged that said plate can only be lifted after releasing the shackle of the padlock.

2. A padlock with means for detecting the unlocking of the same comprising a locking mechanism provided with means for tearing a controlling card or the like placed with the 90 padlock; means for assuring the inviolability of the card while the lock remains in locked condition comprising an element having a sight opening for permitting the inspection of the card without necessitating 95 the unlocking of the padlock, said element being located immediately over the card, and a protecting cover hinged to the casing for movement into closed position over said element and provided with a spring to cause 100 its normal closure.

3. A padlock with means for detecting the unlocking of the same comprising a casing; a locking mechanism operable by a key; a slide controlled by the key, said slide being 105 provided with projections designed to pass through holes formed in a seal card; a spring for holding said slide in its position of rest; a spring actuated bolt having a boss adapted to engage with said slide at a pre-determined point in the travel of the bolt; a pivoted shackle having at its end a recess for engagement with the locking bolt in its locked position; a spring for normally urging the shackle to its locking position; a 110 plate provided with a window of transparent material, hinged to one side of the casing, for movement over the seal card to protect the same, said plate having a portion at its free side bent at right angles and 115 provided with an opening and a recess for the passage and the reception of the shackle; and a cover plate hinged to the plate which covers the card and adapted to move immediately over that plate.

125

4. In a seal lock, the combination of a bolt; means for holding a seal which is susceptible of being mutilated; a key-controlled, endwise-movable slide adapted to withdraw the bolt from locking position and 130

- adapted to be controlled by a key; and means, movable with said slide and adapted to normally project through said seal, for mutilating the seal when the slide is moved 5 in effecting an unlocking movement of the bolt.
5. In a seal lock, the combination of a shackle; a bolt for locking the same; a key-controlled, endwise-movable slide interposed 10 between the bolt and the key for withdrawing said bolt from engagement with the shackle; means for holding a seal card in inaccessible condition while the shackle and bolt are in locked condition; and a projection mounted on the slide and normally extending 15 through the seal card, adapted to deface the seal card when the slide is moved to release the bolt and thus the shackle from locked condition.
- 20 6. In a seal lock, the combination of a shackle; a bolt for locking the shackle; means for operating the bolt; means for carrying a seal; means for defacing the seal incidental to the movement of the bolt operating 25 means; a cover having a sight-opening covered by transparent material for rendering the seal inaccessible from the exterior of the lock while permitting inspection of the seal; a lug carried by the cover and 30 adapted to be engaged by the shackle when the latter is in closed position to lock the cover closed; and a hinged guard to protect the transparent material of the sight opening against damage.
- 35 7. In a seal lock, the combination of a casing; a shackle; locking mechanism in the casing for coöperation with the shackle and provided with seal-mutilating means; and a cover plate hinged at one end to the casing 40 and provided at its other end with a right-

angular flange adapted to extend across the outside of the casing, said flange having a recessed portion for engagement with a nose on the shackle.

8. In a seal lock, the combination of a 45 casing; a shackle pivotally connected thereto at one end and provided adjacent said pivoted end with a nose; locking mechanism in the casing for coöperation with the free end of the shackle and provided with seal-mutilating means; and a cover plate hinged to the casing and provided with a flange disposed on the outside of the casing and having a recessed portion for engagement by 50 said nose. 55

9. In a lock, the combination of a casing; a shackle; a fixed guide within the casing; an endwise-movable spring-controlled bolt 60 slidably mounted in said guide for engagement with the shackle, said bolt having an offset arm; and a key-controlled slide disposed parallel with said bolt and movable endwise into contact with the arm thereof, to forcibly disengage the bolt.

10. In a lock, the combination of a casing; 65 a shackle; a fixed guide within the casing; an endwise-movable spring-controlled bolt slidably mounted in said guide for engagement with the shackle, said bolt having an offset arm; a key-controlled slide disposed 70 parallel with said bolt and movable endwise into contact with the arm thereof, to forcibly disengage the bolt; and a cover plate for the casing hinged thereto at one end and provided at its other end with a flange having 75 a recessed portion for engagement by a lateral nose on the shackle.

In testimony whereof I affix my signature.

CARLOS CAMPANILE.
